(57) **CLAIM**

The ornamental design for an escutcheon, as shown and described.

DESCRIPTION

FIG. 1 is a perspective view of the new design for an escutcheon;

FIG. 2 is a front elevational view of the new design for an escutcheon;

FIG. 3 is a top plan view of the new design for an escutcheon, the bottom plan view being a mirror image;

FIG. 4 is a right side elevational view of the new design for an escutcheon, the left side elevational view being a mirror image; and,

FIG. 5 is a rear elevational view of the new design for an escutcheon.

The broken lines in the Figures are for illustrative purposes only and form no part of the claimed design.
